Des. 205,711
Patented Sept. 13, 1966

205,711

GRENADE FOR DISPENSING GASES, LIQUIDS, OR THE LIKE

Robert W. Schnepte, Jr., 111 Cinder Road, Timonium,
Md.; Francis J. Pilarski, 4618 Raspe Ave., Raspeburg,
Md.; Irwin R. Barr, 110 Martingale Road, Lutherville,
Md.; and David Sylvester, P.O. Box 32, Phoenix, Md.

Filed Sept. 8, 1965, Ser. No. 86,901

Term of Patent 14 years

(Cl. D30—1)

FIG. 1

FIG. 2

FIG.7

FIG.4

FIG.3

FIG. 5

FIG. 6

FIGURE 1 is an isometric view of a grenade for dispensing gases, liquids, or the like, showing our new design.

FIGURE 2 is a top plan view of the grenade of FIGURE 1.

FIGURE 3 is an elevational view as seen from the handle side of the grenade.

FIGURE 4 is an elevational view of the grenade as viewed from a side position spaced 90° from the view of FIGURE 3.

FIGURE 5 is an elevational view taken from a position and in a direction directly opposite from that of FIGURE 3.

FIGURE 6 is an elevational view taken from a position and in a direction directly opposite from that of FIGURE 4.

FIGURE 7 is a bottom plan view of the grenade of FIGURE 1.

We claim:

The ornamental design for a grenade for dispensing gases, liquids, or the like, as shown.
